LIPSTICK HOLDER

Samuel Segal, Brooklyn, N. Y.

Application September 27, 1940, Serial No. 358,702

7 Claims. (Cl. 206—56)

The present invention deals with a functionally and structurally improved lipstick holder and the objects, features, and salient advantages thereof will be more fully understood from the following detailed description considered in the light of the accompanying drawing wherein:

Fig. 1 is an enlarged vertical sectional view of the lipstick holder according to my invention, illustrating the lipstick in its concealed and retracted position.

Fig. 2 is a horizontal sectional view on the line 2—2 of Fig. 1.

Fig. 3 is a vertical sectional view of the holder illustrating the elevator raised to project the cosmetic stick sustained thereby outside of the holder.

Fig. 4 is an exploded and perspective view of the holder, and

Fig. 5 is an enlarged vertical sectional view of slightly modified lipstick support or seat.

According to the invention a lipstick 10 has its lower end threaded into the hollow cylindrical cup or elevator 11 and is seated on the upper face 12 of the split sheet metal substantially annular support or resilient band 14 having a free end or wing 15 carrying the radially extending projection or pin 16 which as shown in Figs. 1 and 4 is appropriately fastened thereto and as illustrated in Fig. 5 is extruded from the body of the band.

The free end or finger 15 is provided with a circumferentially arranged kerf 17 to set off the upper resilient arcuate finger 18 which is bent outwardly at 19 to allow its convex intermediate part to overhang the upper portion of the free end 15 carrying the key or projection 16.

Before assembly the relatively thin metal split band or strip 14 of Fig. 4 is slightly larger in diameter than the diameter of the bore 20 of the cylindrical body of the cup 11, that is to say, the band or strip 14 is normally expanded and when arranged in the bore 20 it is initially manually compressed and subsequently moved downwardly until the projection 16 registers with opening 22 and bowed finger 18 registers with the circumferentially arranged slot 21 above the opening 22 in the cylindrical body of the cup.

Thereafter the body of the band expands and the wing or end 15 automatically shifts outwardly and substantially radially, causing pin 16 to project into and through opening 22 to overhang the body of the cup 11. Also at this time the spring finger 18 resiliently snaps into and through slot 21 to slightly overhang the cylindrical body of cup 11. It follows that the strip 14 is dis-

connectably locked to the cup although spaced from the bottom wall thereof.

With the spring 14 assembled and locked as described within the cup, the body of the band 5 continuously exerts an outward thrust on the surface of the bore 20, since the band 14 tends to expand but is prevented from such expansion by the hollow cylindrical surface of the bore 20 and in such relation wings 15 and 23 which define gap 24 likewise yieldingly and frictionally bear against interior surface of the bore 20.

Having locked the resilient and relatively thin metal band in the cup, the latter may be conveniently positioned within cylindrical metal shell 15 25 which is provided with the vertical guide slot 26 and the annular upper stop rib 27. To this end the lower part of the metal cup 11 is first inserted into the metal shell or casing 25 until pin 16 strikes the upper rib 28. Thereafter the 20 pin is pressed inwardly causing the wing or resilient finger 15 to flex inwardly, and thus the free end of the pin is projected into the bore of the shell. Hence an elastic connection is provided to sustain seat 14 above the bottom wall of the 25 cup 11.

Pursuant to this operation, the protruding arcuate resilient finger 18 is flexed or pushed inwardly to be received within the bore of the shell. The elevator or cup 11 is then rotated to permit 30 pin 16 to snap into the rectilinear guide slot 26. Hence the lipstick carrier or cup 11 is slidably keyed to the shell 25 and reciprocably guided relative thereto although at this time the arcuate spring finger 18 frictionally but, yieldingly bears against the inside cylindrical surface or bore 29, the superimposed finger 18 being shorter than the finger 15, permitting the former to completely project into slot 21 (Fig. 2).

Integral with the split annular band 14 is the 40 brace 30 which is disposed along the diameter of the bore of the body of the cup 11. This brace has an upper face 31 at the elevation of the peripheral upper horizontal surface 12 of the band thereof, and thus surfaces 12 and 31 constitute 45 a rest on which the lower part of the lipstick is positioned and therefore the annular band or strip 14 characterizes a seat limiting the insertion of the lipstick into the cup 11.

For propelling the elevator or cup 11 vertically 50 of the shell 25, a cylinder sleeve 32 is provided. This sleeve surrounds shell 25 and includes the helical cam slot 33 extending along the entire length of the sleeve and projecting into this cam slot 33 is the pin 16. Hence rotation of the shell 55 25 relative to the sleeve or bearing 32 causes pin

16 to ride along the cam slot 33 and thus bearing 32 causes the elevator or cup 11 to be vertically displaced relative to the shell 25 which includes the enlarged knob 34 providing the annular shoulder 35 on which the lower portion of the sleeve 32 is seated while the upper portion of the latter is retained under the stop rib or flange 27, thereby precluding longitudinal displacement of the sleeve 32 relative to the shell 25.

Frictionally and closely surrounding the sleeve 32 is the outside cylindrical sheet metal tube 36 on which is rigidly secured the stop ring 37 defining the stop shoulder 38 which serves to limit the displacement of the cylindrical cap 39 on the tube 36 in closing the latter after which the resilient rib 40 struck out of the body of the tube 36 frictionally holds the cap in place.

Where the cap 39 is removed, rotation of the knob 34 relative to the outside tube or casing 36 likewise causes the rotation of the elevator or cup 11 relative to the fixed sleeve 32 and consequently pin 16 which is guided in slot 26. The pin 16 however as it rotates is always in the helical cam slot and therefore the lower face 41 of the cam slot raises the pin when the shell 25 is rotated in one direction and if shell 25 be rotated in an opposite direction the upper face 42 of the cam slot actuates the pin to move downwardly in the rectilinear slot 26 and of course if pin 16 is actuated the elevator 11 is correspondingly actuated.

By the present arrangement it is therefore apparent that the lipstick 10 may be shifted lengthwise of the holder upon the rotation of shell 25 relative to the outside tube 36 and the cammed sleeve 32 which in fact causes the seat 14 as well as the cup 11 to be bodily displaced or actuated lengthwise of the holder during the rotation of the knob 34, thus if the latter be rotated in one direction the elevator may be shifted to project the lipstick out of the holder and if rotated in an opposite direction the stick may be quickly retracted into the holder.

In the assembled relation of the holder, the seat 14 for the lipstick is positively retained within the cup 11 and the pin is continuously positioned within the cam slot 33 and since the normal tendency of the seat 14 is to expand outwardly, the outer substantially cylindrical surface thereof frictionally although yieldingly abuts the wall of bore 20. Hence the driven pin 16 is always projecting into the cam slot and is prevented from accidentally falling out therefrom. Since the pin is positively positioned within the cam slot of the fixed sleeve 32 and does not overhang the outside surface of the latter, frictional engagement between the free end of the driven pin 16 with the inner surface of the tube 36 is thus precluded, thus insuring the proper positioning of the elastic or resilient support or seat 14 within the cup 11.

Moreover, since the seat 14 is relatively springy it may be quickly assembled with the cup, and thereafter the latter may be readily assembled with shell 25 after which the cam sleeve is fixedly positioned on the knob 34 by the tube 36 and with the parts assembled as described the lipstick is subsequently positioned within the shell 25 and arranged within cup 11 and seated on the vertically yieldable seat 14 which always returns to its normal position shown in Fig. 1 due to its inherent resiliency.

When the elastic seat is assembled with the cup 11 and the latter with shell 25, the lower part of the sleeve 32 may be mounted on the

upper part of the shell 25 to quickly receive the pin of the cup which at this time has been manually located at the upper part of slot 26 and thereafter the sleeve may be brought entirely and easily over the shell 25. It is thus apparent that the holder may be quickly assembled and with ease and after assembly wobbling of the cup relative to the shell is also prevented by the aid of the finger or resilient brush 18 continuously urged outwardly by its own resiliency and therefore bears yieldingly against the wall of the bore 29.

The seat 14 may be said to provide an elastic connection with the cammed sleeve 32 in that it is yieldable although continuously and operatively in engagement with the cam slot through its pin 16, thus providing smooth operation in the matter of adjusting the lipstick and preventing sticking or jamming of the pin 16 with sleeve 32 or with the tube 36 during such adjustment.

Various changes may be made in details of construction and arrangement of parts without departing from the spirit of the invention or sacrificing any of the advantages thereof inherent therein.

25 I claim:

1. In combination, a resilient seat comprising an expandible and contractible substantially annular strip defining a pair of spaced terminal wings, a brace carried by one of said wings, a resilient tongue extending laterally of the other wing of said pair, a hollow member closely surrounding said strip for holding said strip under compression and including an opening, a projection extending from said strip and interlocking with said member, said tongue yieldingly extending into said opening, a shell rotatably surrounding said member and including a slot for slidably receiving said projection and frictionally engaging said tongue, and means for driving said projection to displace said seat relative to said shell.

2. In combination, a resilient seat comprising an expandible and contractible substantially vertically split strip defining a pair of spaced terminal wings, a brace integrally carried by one of said wings, a finger extending laterally of the other wing of said pair, a hollow member closely surrounding said seat for holding said seat under compression and including an opening, a projection extending from said seat and sustained by said member, said tongue yieldingly extending into said opening, a shell rotatably surrounding said member and including a slot for slidably receiving said projection and frictionally engaging said tongue to sustain said seat relative to said shell, and means for driving said projection to displace said seat relative to said shell.

3. In combination, a resilient seat comprising an expandible and contractible substantially annular and vertically split strip defining a pair of spaced terminal arcuate wings, a brace carried by one of said wings and extending substantially transversely of said strip, a resilient finger extending laterally of said other wing of said pair, a hollow annular member closely surrounding said seat for holding said seat under compression and including an opening, a projection extending from said seat and interlocking with said member, said tongue yieldingly extending into said opening, a shell rotatably surrounding said member and including a slot for slidably receiving said projection to movably guide said seat and frictionally engaging said tongue to sustain said seat relative to said shell, and means for driving

said projection to displace said seat relative to said shell.

4. In combination, a substantially annular resilient strip including a laterally offset tongue, a projection extending from said strip, a hollow member for housing said strip and for compressing the latter and including means for holding said projection and including an opening for receiving said tongue, a shell frictionally cooperating with said tongue and surrounding said member and having a slot for movably guiding said projection, and means to drive said projection to displace said strip relative to said shell.

5. In combination, a hollow resilient strip including a laterally offset tongue, a projection extending from said strip, a hollow member for housing said strip and for compressing the latter and including means for holding said projection and including an opening for receiving said tongue, a shell surrounding said member and abutting said tongue and having a slot for movably guiding said projection, and means to drive said projection to displace said strip relative to said shell.

6. In combination, a substantially annular ver- 25

tically split resilient strip including a laterally offset tongue, a projection extending from said strip, a hollow member for housing said strip and for compressing the latter and including means for holding said projection and including an opening for receiving said tongue, a shell yielding abutted by said tongue and surrounding said member and having a slot for movably guiding said projection, and means to drive said projection to displace said strip relative to said shell.

7. In combination, a substantially annular resilient vertically split strip including a laterally offset tongue, a projection extending from said strip, a hollow annular member for housing said strip and for compressing the latter and including means for holding said projection and including an opening for receiving said tongue, a shell yielding abutted by said tongue and surrounding said member and having a slot for movably guiding said projection, means to drive said projection to displace said strip relative to said shell, and a brace carried by said strip and extending substantially transversely thereof.
